UNITED STATES PATENT OFFICE.

HARRY R. GEER, OF JOHNSTOWN, PENNSYLVANIA.

UNIVERSAL MILL.

1,392,489.

Specification of Letters Patent.

Patented Oct. 4, 1921.

Application filed July 26, 1920. Serial No. 398,977.

To all whom it may concern:

Be it known that I, HARRY R. GEER, a citizen of the United States, and a resident of the city of Johnstown, county of Cambria, 5 and State of Pennsylvania, have invented certain new and useful Improvements in Universal Mills; and I do hereby declare the following to be a full, clear, and exact description of the invention, such as will enable others skilled in the art to which it 10 appertains to make and use the same.

My invention relates to improvements in rolling mills and particularly to rolling mills of the class known in the art as universal mills and is designed to provide improved housings, supports and guides for the vertical rolls of such mills.

One of the objects of my invention is to provide a strong and rigid mechanism 20 adapted to support and guide the vertical rolls of a mill whereby all thrusts are properly transmitted to the frame of the mill and also adapted to permit lateral adjustment of the rolls to form the desired passes. 25 Another object of my invention is to provide for the vertical rolls interchangeable housings which can be readily removed from and remounted in the mill without disturbing the integrity and adjustment of the 30 frame of the mill.

In prior rolling mills, provided with vertical rolls, the vertical roll housings have been made right and left hand housings respectively because of the construction of the 35 guide bars or frames which supported the housings but my mill is made with its vertical roll housings identical and interchangeable and my invention comprises such identical and interchangeable vertical 40 roll housings mounted in and supported by an upper and a lower guide frame, each of unitary construction. These one piece guide frames, once secured to the frame of the mill of which they form a part, do not 45 have to be removed or the adjustment of the frame of the mill in any way disarranged when for any reason it becomes necessary to change rolls. In combination with the one piece guide frames, the interchangeable vertical 50 roll housings, which I provide, simplify the construction of the mill very much and eliminate the maintenance of a great variety of spare parts for contingencies 55 arising from general use and accidents or requiring replacement of parts.

My invention comprises a pair of vertical

rolls mounted in interchangeable housings which are supported in and guided by an upper and a lower guide frame, each of unitary construction. These one piece guide 60 frames extend between the end frames to which they are secured and form therewith the frame of the mill. In connection with the above I show a driving arrangement for the vertical rolls and means adapted to 65 move said rolls laterally whereby the desired pass may be obtained together with means adapted to indicate the size of each pass.

Having thus given a general description 70 of my invention, I will now, in order to make the matter more clear, refer to the annexed three sheets of drawings, which form part of this specification, and in which like characters refer to like parts.

Figure 1 is a vertical and partly sectional elevation of the vertical rolling mechanism of a universal mill embodying my invention; Fig. 2 is a top plan view of the rolling mechanism shown in Fig. 1, the left-hand bevel pinion being shown in section with its bearing cap removed; Fig. 3 is a horizontal longitudinal section on the line III—III of Fig. 1; Fig. 4 is a vertical transverse section on the line IV—IV of Fig. 1; 85 Fig. 5 is a horizontal transverse section on the line V—V of Fig. 6; Fig. 6 is a vertical longitudinal section of my improved interchangeable vertical roll housing; Fig. 7 is a horizontal transverse section on the line 90 VII—VII of Fig. 6; Fig. 8 is a vertical elevation of one of the motor operated gear trains which rotate the adjusting screws; Fig. 9 is a top plan view partly in section showing the driving connection between the 95 motor and the gear train shown in Fig. 8; Fig. 10 is a top plan view of my improved upper guide frame; Fig. 11 is a vertical longitudinal sectional elevation on the line XI—XI of Fig. 10; Fig. 12 is a top plan 100 view of my improved lower guide frame; Fig. 13 is a vertical longitudinal sectional elevation on the line XIII—XIII of Fig. 12; Fig. 14 is a vertical transverse sectional elevation on the line XIV—XIV of Fig. 105 13; Fig. 15 shows a vertical elevation and a transverse section of one of the guide frame side cheek plates; Fig. 16 is a bottom plan view of one of the guide frame top cheek plates; Fig. 17 shows a vertical elevation 110 and a transverse section of one of the lower side bearing plates used on the vertical roll

5 housings; Fig. 18 shows a plan and an elevation of one of the top bearing plates used on the vertical roll housings; Fig. 19 shows a vertical elevation and an end elevation of 10 one of the upper side bearing plates used on the vertical roll housings, the position of the key and keeper being shown in dotted lines on the vertical elevation; and Fig. 20 is a vertical elevation of the key used to 15 wedge the upper side bearing plate in the vertical roll housing.

Referring now to the characters of reference on the drawings:—Bed plates 1, end frames 2 and 3 secured thereto and lower 15 and upper guide frames 4 and 5 respectively, which extend between the end frames 2 and 3 and are secured thereto by bolts or otherwise, comprise the frame for the vertical rolling mechanism.

20 The lower guide frame 4 is of unitary construction and comprises two side portions 6 and 6^a which are connected by two transverse end portions 7 and 8 and an intermediate transverse portion 9. The two side portions 6 and 6^a and the transverse portions 7, 25 8 and 9 thus form two openings 10, two opposed sides of which form lower slideways for the housings 11 in which the necks of the vertical rolls 12 are journaled. The 30 slideways are provided with side cheek plates 13 which are secured to the inner sides of the side portions 6 and 6^a of the guide frame 4 by bolts which can be inserted through hand holes 14 in the outer 35 side of the side portions 6 and 6^a. The side portions 6 and 6^a and the transverse end portions 7 and 8 of the lower guide frame 4 are preferably formed hollow in order to insure minimum weight for maximum 40 strength and rigidity while the intermediate transverse portion 9 is preferably of I-shaped section.

45 The side portions 6 and 6^a of the lower guide frame 4 are provided with integrally formed brackets 15 which extend downwardly therefrom and are adjacent to the ends of the intermediate transverse portion 9. The brackets 15 engage the shoes of the bed plates 1 and form rigid central supports for the lower guide frame 4. The 50 transverse end portions 7 and 8 of the lower guide frame 4 have formed integrally therewith enlarged portions 16, the outwardly extending ends of which set in openings in 55 the end frames 2 and 3. The enlarged portions 16 are provided with a chamber 17 and an opening 18. Adjusting screw nuts 19 which are secured in the chambers 17, so as to prevent rotation therein, engage the 60 lower adjusting screws 20 which pass through the openings 18. In order to provide for the difference in elevation of the vertical rolls 12 the transverse end portion 8 of the lower guide frame 4 is formed 65 deeper than the transverse end portion 7 to

allow the adjusting screws to be carried at the proper heights.

Bosses 21 on the top of the side portions 6 and 6^a of the lower guide frame 4 each side of the intermediate transverse portion 70 9 form seats for bearings 22 which are secured to the guide frame 4 by bolts or otherwise. The bearings 22 have journaled therein in the necks of the table rolls 23. A pedestal 24 is secured at the top of the intermediate transverse portion 9 of the lower guide 75 frame 4 between the table rolls 23 to support the piece to be rolled as it passes between the vertical rolls 12 thereby preventing any sag or downward deflection of the 80 piece. Grooves 25 in the side portion 6^a of the lower guide frame 4 are adapted to receive the flanges 26 of the horizontal roll housings and the flanges 26 are secured in the grooves 25 by wedges 27 as shown in 85 Fig. 3.

The upper guide frame 5 is of unitary construction and comprises two side portions 28 and 28^a which are connected by two transverse end portions 29 and an intermediate transverse portion 30. The two side portions 28 and the transverse portions 29 and 30 thus form two openings 31, two opposed sides of which form upper slideways for the housings 11 in which the necks 95 of the vertical rolls 12 are journaled. The side portions 28 and the transverse end portions 29 of the upper guide frame 5 are preferably formed hollow in order to insure minimum weight for maximum 100 strength and rigidity while the intermediate transverse portion 30 is preferably of I-shaped section. The side portions 28 and 28^a are of substantially L-shaped outline in order to provide not only vertical slideways, but 105 also horizontal slideways which are arranged at different heights each side of the intermediate transverse portion 30 in order to allow for the difference in elevation of the vertical rolls 12. The vertical slideways 110 are provided with side cheek plates 13 and the horizontal slideways with top cheek plates 32 secured thereto by bolts which can be inserted through the handholes 33 in the outer side of the side portions 28 and 28^a. 115

120 Each of the side portions 28 and 28^a of the upper guide frame 5 is provided adjacent to the ends of the intermediate transverse portion 30 with a raised platform 34 formed integrally with the guide frame 5. The platforms 34 support the bearing member 35 which is secured thereto by bolts or otherwise. The bearing member 35 is provided with two bearings 36 at different heights in 125 which are journaled the inner ends of the drive shafts 37 and the central journal bearing 38 for the main drive shaft 39. The dial mechanism 40 which indicates the roll pass is also mounted on the bearing member 35. 130

The transverse end portions 29 of the upper guide frame 5 have formed integrally therewith enlarged portions 41, the outwardly extending ends of which set in openings in the end frames 2 and 3. The enlarged portions 41 are provided with a chamber 42 and an opening 43. Adjusting screw nuts 19 which are secured in the chambers 42, so as to prevent rotation therein, engage the upper adjusting screws 44, which pass through the openings 43.

Grooves 45 in the side portion 28^a of the upper guide frame 5 are adapted to receive the flanges 26 of the horizontal roll housings and the flanges 26 are secured in the grooves 45 by wedges 27 as is shown in Figs. 2 and 10.

The vertical roll housings 11 are so constructed as to be identical and interchangeable and each housing is provided with lower and upper journal boxes 46 and 47 formed integrally therewith and having mounted therein bearings in which the necks of the vertical rolls 12 are journaled. The guide frames 4 and 5 support the housings 11 and the lower and upper journal boxes 46 and 47 thereof fit between and are guided by the slideways of the guide frames 4 and 5. The lower journal box 46 is provided on two opposite sides with lower side bearing plates 48 which slidably engage the side cheek plates 13 on the slideways of the lower guide frame 4. The lower side bearing plate 48 has three flanged edges, the intermediate one of which sets in a slot 49 in the side of the lower journal box 46 and the other edges grasp the faces thereof, thus serving to hold the lower side bearing plate 48 in position. These side bearing plates 48 are mounted on the cheek plates 13 in reversed position to allow for the different heights of the slide ways at the ends of the guide frame 4. The horizontal flanged edge of the plate 48 is at the lower edge of the bearing plate at one end of the guide and at the upper edge thereof on the other end of the guide frame 4 as indicated in Fig. 4 to engage the slot 49 in the lower journal box 46 in each case. The upper journal box 47 is provided on the two correspondingly opposite faces with upper side bearing plates 50 which slidably engage the side cheek plates 13 on the slideways of the upper guide frame 5. The upper side bearing plate 50 has a raised and tapered central portion 51 which engages a slot 52 in the sides of the upper journal box 47 and is secured thereto by the key 53 and bolts through the flanges 54 and the keeper 55 which retains the key 53. The upper side bearing plate 50 is also provided with an outwardly extending flange 56 which slidably engages the lower edge of the side cheek plates 13.

The lower journal box 46 is provided with a vertical roll bottom bearing 57 fitted with

a flanged bushing 58 in which the lower neck of the vertical roll 12 is journaled and a thrust bearing comprising a roller bearing 59 underneath the follower 60 on which the end of the vertical roll 12 rests. The external 70 diameter of the lower part of the bottom bearing 57 is less than that of the upper part while the corresponding internal diameters of the lower journal box 46 are arranged in reverse order. The projecting 75 portions of the bottom bearing 57 and the lower journal box 46, thus formed, interlock and prevent any downward movement of the bottom bearing 46. Bolts in the forked openings 61 in the sides of the lower journal 80 box 46 serve to clamp the bottom bearing 57 securely therein. Each of the vertical rolls 12 has at the top of the lower neck a collar 62 formed thereon which rests upon the flange of the bushing 58 and is shaped to deflect scale, etc., away from the bearing. The upper journal box 47 is provided with a journal bearing comprising a bearing 63 and a cap 64 secured to each other and to the upper journal box 47 by bolts 65. 90

Extending upwardly and laterally from the top of each vertical roll housing 11 adjacent to the upper journal box 47 is a bracketed portion 66 formed integrally with the housing and provided with a thrust bearing 67 in which is journaled the bevel gear 68. The bracketed portion 66 overhangs the sides of the upper journal box 47 and the overhanging parts are provided with top bearing plates 69 which engage slots therein 100 and are adapted to sliding contact with the top cheek plates 32 on the horizontal slide-ways of the upper guide frame 5.

The bevel gears 68 rotate with and reciprocate on the drive shafts 37 and are always 105 in mesh with the bevel gears 70 on the upper ends of the vertical rolls 12. The vertical rolls 12 are thus positively driven at all points of lateral adjustment through the main drive shaft 39 and the spur gears 71 110 thereon which mesh with the overhung spur gears 72 on the drive shafts 37.

The lateral adjustment of the vertical rolls 12 toward each other is accomplished by the rotation of the lower and upper adjusting 115 screws 20 and 44 which bear rotatively against the backs of the lower and upper journal boxes 46 and 47 of the vertical roll housings 11. The lateral adjustment of the vertical rolls 12 away from each other is 120 accomplished by the action of the fluid pressure on the pistons 73 in the pull back cylinders 74. The pistons 73 are mounted on piston rods 75 to the ends of which are secured cross heads 76 which set in central 125 pockets 77 formed on the back of the vertical roll housings 11. Since the pistons 73 are always subject to fluid under pressure the vertical roll housings 11 will at all times be firmly held against the ends of the adjusting 130

screws 20 and 44 and will move in or out according to the direction of rotation of the adjusting screws 20 and 44.

The adjusting screws 20 and 44 are operated by motor driven gear trains, see Figs. 1 and 8, which are housed between the end frames 2 and 3 and the gear casings 78 secured thereto. The gears 79 are splined on the adjusting screws 20 and 44 while the idler gear 80, which meshes with the gears 79, is journaled on the pull back cylinder 74 and the drive gears 81 are keyed to the inner ends of the jack shafts 82. The jack shafts 82 are mounted in journal bearings 83 secured to the brackets 84 which support the reversible motors 85 and are secured to the end frames 2 and 3. The jack shafts 82 are geared to the motor shafts 86 and in order that the vertical rolls 12 may move laterally in synchronism the motor shafts 86 are coupled to an equalizing shaft 87 journaled near the ends in the end frames 2 and 3 and centrally in the bearing 88 which is secured to the top guide frame 5.

In a mill used for rolling metals and particularly steel the rolls are subject to severe usage which makes it necessary to remove and dress the rolls from time to time and also to replace worn out rolls by new ones. Such roll changes involve shutting down the mill and mean a consequent loss of valuable operating time. Therefore any device which simplifies the changes of rolls and reduces the time thereof and at the same time furnishes a strong and rigid mechanism capable of heavy duty is much desired. I have fully discussed the strong and rigid construction of my vertical rolling mechanism and will now describe the method of changing rolls in order to show the particular advantages of my invention.

The method of changing either of the vertical rolls 12 and the housing 11 thereof is as follows:—If the right hand roll is to be removed, the dial operating screw 90 should first be disconnected from the housing 11, otherwise the procedure is the same for both rolls. In order to provide working clearance the vertical rolls 12 are preferably advanced toward the center of the mill by the adjusting screw mechanism. The split thrust collar 89 is removed from the drive shaft 37 by disconnecting the bolts which hold the thrust collar 89 on the drive shaft 37. The drive shaft 37 is then withdrawn outwardly from the bevel gear 68 through the drive shaft bearing in the end frame 2 or 3. The vertical rolls 12 are then separated laterally to about their extreme positions by reversing the rotation of the adjusting screws 20 and 44 and the action of the fluid pressure pull-back cylinders 74. The crosshead 78 is then disconnected from the piston rod 75. An eye-bolt is now screwed into a threaded socket in the top of

the vertical roll 12 and a crane hook inserted therein. The bolts holding the keepers 55 and the upper side bearing plates 50 of the upper journal box 47 are then removed thus freeing the keys 53 which may be withdrawn to release the upper side bearing plates 50. The upper side bearing plates 50 are then withdrawn and the vertical roll housing 11 is free to move vertically. As the housing 11 is raised by the crane the lower side bearing plates 48 are slipped off from the lower journal box 46 and the housing 11 is lifted to clear the mill. Inasmuch as the housing and the roll unit are interchangeable a spare unit kept on hand for either end of the mill can now be placed in the mill by following the above steps in reverse order.

It is thus evident that my invention provides a rapid and facile means adapted to provide for roll changes without interference to the adjustment of the frame of the mill or undue disturbance to the correlation of the parts thereof and further provides an interchangeable roll housing which greatly reduces the maintenance of spare parts, always a costly item in rolling mill upkeep. Furthermore the construction of the frame, particularly with reference to my improved guide frames, is such as to insure that all the thrusts of rolling are properly transmitted and distributed thereby avoiding any deformation or distortion of the various parts of the mill in their relation to each other.

Although I have shown and described my invention in considerable detail, I do not wish to be limited to the exact and specific details thereof, as shown and described, but may use such modifications in, substitutions for, or equivalents thereof, as are embraced within the scope of my invention, or as pointed out in the claims.

Having thus described my invention, what I claim and desire to secure by Letters Patent is:—

1. In a universal mill, a guide frame of unitary construction, comprising two side portions connected by a plurality of transverse portions, said guide frame constituting a support for the upright rolls.
2. In a universal mill, end frames, a one piece guide frame extending therebetween and secured thereto and comprising a pair of side portions and a plurality of transverse portions formed integrally therewith, said guide frame constituting a support for the upright rolls.
3. In a universal mill, end frames, a guide frame of unitary construction extending therebetween and secured thereto, said guide frame comprising two side portions connected by two transverse end portions, and an intermediate transverse portion, and longitudinal slideways in the openings formed by

- said side and transverse portions, said guide frame constituting a support for the upper right rolls.
4. In a universal mill, end frames, a pair of one piece guide frames extending therebetween and secured thereto, each of said guide frames comprising two side portions connected by two transverse end portions and an intermediate transverse portion, and 10 slideways in the windows formed by said side and transverse portions.
5. In a universal mill, end frames, a lower guide frame of unitary construction extending therebetween and secured thereto, said 15 guide frame comprising two side portions connected by a plurality of transverse portions formed integrally therewith and brackets extending downwardly from the side portions of the guide frame and adapted to 20 engage the bed plates of the mill and to furnish thereby a rigid support for the guide frame.
6. In a universal mill, end frames, an upper guide frame of unitary construction extending therebetween and secured thereto, said 25 guide frame comprising two side portions connected by a plurality of transverse portions formed integrally therewith, and platforms above said side portions formed 30 integrally therewith and adapted to support a bearing member secured thereto.
7. In a universal mill, end frames, lower and upper guide frames extending therebetween and secured thereto, each of said 35 guide frames comprising two side portions connected by two transverse end portions and an intermediate transverse portion formed integrally therewith, the openings 40 between said side and transverse portions being provided with slideways and adapted to support and guide a pair of vertical roll housings.
8. In a universal mill, end frames, lower and upper guide frames extending therebetween and secured thereto, each of said 45 guide frames being of unitary construction and comprising two side portions connected by two transverse end portions and an intermediate transverse portion and having enlarged portions formed integrally with said 50 transverse end portions, said enlarged portions containing a chamber provided with an adjusting screw nut and an opening through which an adjusting screw passes to engage said nut.
9. In a rolling mill, an interchangeable vertical roll housing of unitary construction comprising a flanged portion and upper and lower journal boxes formed integrally therewith and a bracketed portion extending upwardly and laterally therefrom and provided 60 with a thrust bearing in which is journaled a sliding bevel gear adapted to mesh with a bevel gear on the upper end of the roll, 65 means for supporting and guiding said hous-
- ing, means for rotating said sliding bevel gear and means for laterally adjusting said roll.
10. In a universal mill, end frames, upper and lower guide frames of unitary construction extending therebetween and secured thereto, slideways in said guide frames adapted to guide and support a pair of laterally adjustable and interchangeable roll housings in which are journaled vertical 75 rolls, means for laterally adjusting said housings and means for rotating the rolls.
11. In a universal mill, end frames, upper and lower one piece guide frame castings extending therebetween and secured thereto, 80 slideways in said guide frames provided with side and top cheek plates, interchangeable roll housings provided with side and top bearing plates and supported by the slideways of said guide frames, vertical 85 rolls journaled in said interchangeable housings, means for rotating said rolls and means for laterally adjusting said interchangeable housings to obtain any desired width of roll pass.
12. An interchangeable roll housing unit for vertical rolls, comprising a casting having upper and lower journal boxes and an upwardly and laterally extending bracketed portion provided with a thrust bearing, a 90 journal bearing secured in said upper box, a bottom journal and roller thrust bearing secured in said lower box, a vertical roll journaled in said bearings and provided with a bevel gear secured to the upper end 95 thereof, a bevel pinion journaled in the thrust bearing of said bracketed portion, adapted to reciprocate on a drive shaft and always meshed with the bevel gear on the vertical roll, side bearing plates on two opposed faces of the lower journal box, and top bearing plates at the upper end of said housing.
13. In a rolling mill, end frames, guide frames adapted to support and guide the 100 housings of a pair of vertical rolls, each of said guide frames comprising a single casting extending between the end frames to which it is secured and having two openings therein, two opposed faces of each of 105 which form slideways for the vertical roll housings.
14. In a universal mill, end frames, upper and lower guide frames each of unitary construction extending therebetween and secured thereto, each of said guide frames comprising two side portions and a plurality of transverse portions, grooves in one of the side portions of each of said guide frames adapted to receive the flanges of the horizontal roll housings and means for securing 110 said flanges in said grooves.
- In witness whereof I hereunto affix my signature.
- HARRY R. GEER.
